GUTTER HANGER

Benjamin Nord, Bayside, N. Y., assignor, by
mesne assignments, to Whitney Metal Products
Corp., New York, N. Y., a corporation of New
York

Application October 7, 1931. Serial No. 567,370

5 Claims. (Cl. 108—29)

This invention relates to gutter hangers in general, and particularly to that part of a gutter hanger known in the trade as "circle", and to the method of manufacturing the latter.

5 Gutter hangers or eaves trough supports are well known in the art and various attempts have been made heretofore to so construct particularly the "circle" of the hangers, as to not only provide an adequate support for the gutter but also to 10 prevent torsional distortion of the "circle", often caused during the mounting thereof to the roof edges, and which will withstand deformation induced by the load to which the "circle" is subjected, when the trough or gutter is filled with 15 rain water or ice. Such attempts resulted in rather complicated structural "circle" formations, which more or less answered the purpose for which they were intended, however, the expense involved usually made them prohibitive in 20 price and therefore restricted their marketability.

The present invention has for its prime object to provide a sturdy "circle", which will withstand the roughest abuse of handling and attaching 25 it, and which will effectively support excessive loads without detriment of any kind to the material employed in its construction, and which at the same time can be manufactured less expensively than any other device of similar or equal 30 sturdiness heretofore produced.

Another object of this invention is the process or method whereby a "circle" of the above stated qualities may be produced at the minimum expenditure of material and labor.

35 Another object of this invention is to provide a "circle" composed substantially of one solid bar, formed into the proper circular shape and equipped with a positive shank guide and a gutter edge hook, the two latter pieces made of lighter 40 metal than employed in the formation of the "circle", but immovably secured to the latter.

In order to facilitate the understanding of this invention more readily, a general explanation of the process of manufacturing is thought advantageous before the detailed description of the device is continued. A stock bar is cut to the proper size and a portion of one of its edges is split; then the bar is curved to the desired radius and the split edge is swedged in such a manner that the 45 swedged portion is forced sideways outwards and the bar material itself is compressed over the entire length, corresponding to the swedged portion. This swedged edge formation forms the seat for the gutter, and through the compression 50 of the bar material the latter is greatly strength- 55

ened, since its molecular arrangement is changed to a greater density than that prevailing in the original bar, prior to the swedging and compression operations.

Now the "circle" is trimmed to the desired 60 conventional shape, and at the heel of the "circle" there is formed from the bar material a vertical rib, provided with a vertical row of apertures, adapted to receive attaching bolts. At the same time the upper end of the heel is 65 formed to a predetermined recessed shape for receiving a hook, adapted to hold the inner edge of the trough in place, and simultaneously there is attached to the "circle" a guide member, designed to form a bearing against which rests the 70 lower end of an attaching shank.

From the foregoing general description of the manufacturing method of the device, it becomes evident that an entirely new article in the gutter hanger line is produced, which has marked 75 superiority over similar present day devices, and its advantages may be enumerated as follows:

The use of stock bar material, minimum weight, maximum strength, resisting torsional deformation and breakage, simplicity of manufacture, 80 inexpensiveness, durability, minimum of bulkiness, ready attachability and minimum waste of material, which advantages may be readily appreciated by the man familiar with this line of business.

Having thus generally explained the article, the foregoing and further objects of this invention will become more fully apparent from the following detailed description thereof, in conjunction with the accompanying drawings, forming 90 part of this disclosure, but by no means intended to restrict the latter to the actual showing, and in which

Fig. 1 is a top view of my device, partially in section, taken on line 1—1 of Figure 2. 95

Fig. 2 is a side elevation of my device including a trough or gutter.

Fig. 3 is a heel end view of the device.

Fig. 4 is an enlarged cross-sectional view taken on line 4—4 of Figure 2 with the trough omitted. 100

Fig. 5 is an enlarged cross-sectional view taken on line 5—5 of Figure 2, showing my device in conjunction with a shank and illustrating the shank guide in cross section.

Fig. 6 is a side and end view of a stock bar, from 105 which the "circle" is formed.

Fig. 7 is a side elevation of the same bar curved to the desired radius.

Fig. 8 is a side elevation of the "circle" after 110 the swedging operation and indicating in broken

lines the contours of the future "circle" after trimming.

Referring now to Figures 6, 7 and 8, numeral 10 denotes a stock bar, preferably made of rolled 5 copper of uniform cross section, which is curved edgewise at a given radius, as shown in Figure 7, so as to form a "circle" portion 11, and a heel portion 12.

The upper edge of the bar is split, as indicated in 10 Figures 1, 4 and 8 at 13, so as to facilitate the spreading of the upper edge during the swedging operation to which the curved bar is subjected as indicated in Figure 8. The swedging operation 15 consists of compressing the bar edgewise over the length of cut 13, whereby a laterally extending ledge 14 is formed at both sides at the upper edge of the bar. This ledge is broadest at the vertical center line of the "circle", and diminishes towards both ends of cut 13. The thus 20 formed ledge constitutes a broad supporting area for the gutter and at the same time provides a stiffening flange against torsional deformation. Yet the ledge is not too broad to make the device objectionably bulky.

25 During the formation of the ledge, the swedging operation causes the stauching of the bar material, whereby the latter is considerably hardened and made tougher than the rest of the bar, and therefore causes a strengthening of that portion of the "circle" which is subjected to greatest 30 load.

Following the swedging and compression operations, the "circle" is trimmed to conventional form, as indicated by the broken lines of Figure 8. 35 During this trimming operation or thereafter the heel portion is reinforced by the formation of vertical rib 15 provided with a plurality of holes 16, through one of which passes an attaching bolt 17, adapted to connect the "circle" with shank 18, (see Figures 1, 2 and 3). Rib 15 registers with the channeled depression of shank 18, the construction of the latter being well known.

40 At the upper end of heel portion 12 there is provided a transverse channel formation 19, adapted 45 to receive a hook 20 designed for holding down the inner edge of trough or gutter 21. This hook is securely fastened in channel formation 19 by means of rivet 22 or other suitable fastening devices.

50 Between the inner ledge end of the "circle" and the heel portion there is attached to the "circle" a shank guide 23, which is made of lighter material than used in the formation of the "circle". The same lighter material is used for the formation 55 of the hook 20. The attachment of guide member 23 is accomplished by forcing the material of the guide member into the material of the "circle" and securing the two pieces together by means of a rivet, as indicated at 24 in Figure 5. 60 Guide member 23 serves not only as guide, but also as a bearing provision for the "circle" and at the same time serves as reinforcement for the latter at the portion between the heel and the ledged ring material.

65 The outer end of the "circle" is shaped to a conventional hook form 24, for receiving either a clip (not shown), adapted to engage recess 25 of the hook or a wire loop 26, which latter is passed through an aperture 27 formed in the 70 hook end. Either the clip (not shown), or wire loop 26 serves for securing the outer, usually rolled edge 28 of the gutter to the "circle".

75 From the foregoing it becomes evident that the formation of the gutter seat or ledge 14 not only provides a proper support for the gutter, but also

reinforces and strengthens the "circle" material both laterally and longitudinally, so that a distortion in any direction, due to handling or load, is effectively counteracted. In the drawings specific forms of the present invention are shown, and it is obvious that modifications and improvements may be incorporated therein, without departing from the broad scope or sacrificing any advantages of the disclosure, and I therefore reserve for myself the right to make changes and improvements therein within the scope of the appended claims.

I claim:

1. A gutter hanger circle comprising a flat metal bar formed to the shape of a "circle", a gutter seat or ledge, swedged-out symmetrically from the upper edge of said bar, and extending sidewise therefrom, being broadest at the vertical center line of the "circle" and diminishing in width towards, and terminating short of both ends thereof, whereby the bar ends retain their flat surfaces the portion of the metal beneath said ledge having greater molecular density than the rest of the bar, a vertical rib formed in, and projecting beyond the flat surface of the heel portion of the "circle" and constituting a reinforcement for said heel portion and provided with a plurality of bolt receiving apertures, a recess formed at the upper end of the heel portion, a hook member secured in said recess and serving for engaging the inner edge of a gutter, the outer end of the "circle" terminating in a clip hook and provided with an aperture, a wire loop engaging said aperture and serving for securing the outer edge of the gutter to the "circle", and an external shank guide secured to said "circle" between the heel portion and the inner end of the ledge of the "circle."

2. A gutter hanger circle formed from substantially one piece of a flat metal bar having an outwardly swedged ledge or gutter seat formed 115 at its upper or inner edge and being substantially symmetrical to its center plane, and being substantially symmetrical to the center planes of the device, said seat terminating short of the circle ends; the material below said ledge having 120 greater molecular density than the rest of the circle material, a vertical rib formed in, and projecting beyond the flat surface of the heel portion of the "circle" and constituting a reinforcement for said heel portion and provided with a 125 plurality of bolt receiving apertures, a recess formed at the upper end of the heel portion, a hook member secured in said recess and serving for engaging the inner edge of a gutter; the outer end of the "circle" terminating in a clip 130 hook and provided with an aperture, a wire loop engaging said aperture and serving for securing the outer edge of the gutter to the "circle", and a shank guide secured to said "circle" between the heel portion and the inner end of the ledge 135 of the "circle".

3. In a gutter hanger circle, a flat bar shaped to form a "circle" and having a swedged-out seat or ledge at its upper or inner edge, the material of the circle beneath the ledge being of greater molecular density than the rest of the bar, a vertically disposed reinforcement formed from the bar material at the heel portion of the circle, a transverse channel formed at the upper terminus of the heel portion, a hook member for engaging the inner edge of a gutter fixedly secured in said channel, shank guide means secured to the side of the circle below said reinforcement, and means provided at the outer end 145 of

of the circle for engaging the outer bead of a gutter. formation, means operatively associated with the latter for securing the outer bead of a gutter to the circle.

4. In a gutter hanger circle, a flat bar shaped to form a "circle" diminishing in width from its heel portion to its outer end, a swedged-out gutter seat or ledge formed at the inner or upper edge of the circle, the circle material beneath the ledge having a greater molecular density than the rest of the bar, a vertically disposed reinforcement formed from the bar material and extending over the major portion of the heel end of the circle, a channel provided at the upper terminus of the heel end, a gutter engaging hook fixedly secured in said channel, a vertical shank guide disposed below the reinforcement and secured at one face of the circle, the outer circle end terminating in a perforated hook 80
5. In a gutter hanger, a circle formed from a flat bar provided with a swedged-out inner or upper gutter receiving ledge, the material below the ledge having a greater molecular density than the rest of the bar, a reinforcement forced out from and extending along the heel portion of the circle, separate means for engaging the inner edge of a gutter fixedly secured at the upper terminus of the heel portion, separate shank guide means disposed below said reinforcement and fixedly secured to the circle material, the outer end of the circle provided with adjustable means for engaging the outer bead of a gutter. 85
